C. H. Eddy,

Shutter Fastener.

No 62,947.

Patented Mar 19, 1867.

United States Patent Office.

CHARLES H. EDDY, OF AUBURN, NEW YORK, ASSIGNOR TO HIMSELF
AND THEODORE J. DICKERSON, OF SAME PLACE.

Letters Patent No. 62,947, dated March 19, 1867.

IMPROVED BLIND AND SHUTTER FASTENER.

The Schedule referred to in these Letters Patent and making part of the same.

TO WHOM IT MAY CONCERN:

Be it known that I, CHARLES H. EDDY, of the city of Auburn, in Cayuga county, and State of New York, have invented a new and improved Mode of Fastening Blinds and Window Shutters by means of a lever and hooks held in position by the lower casement of the sash; and I do hereby declare the following to be a full, clear, and exact description of the same, reference being had to the accompanying drawings, making a part of this specification, and to the letters of reference marked thereon.

The object of this invention is to prevent the shutters being opened from the outside of the building, by means of hooks engaging loops or offsets secured to the blinds or shutters, and when the said hooks are engaged with said offsets or loops they are held in that condition by means of the lower casement of the sash, and are by that means held firmly against any attempt from without to disengage them.

In order that others skilled in the art may know how to make and use my invention, I will proceed to describe its construction and mode of operation. In the drawing—

Figure 1 represents a window with the blinds or shutter frames A and B open.

The loops C D on the same engage the notches E and F on the outward end of the lever G. Said lever is jointed to the sill H of the window frame at G, as shown in fig. 2, by means of the staple I. The end J, of the lever G, extends under the lower casement of the window sash K, and when the blinds or shutters are closed, together, and the hooks E and F engage the loops C and D, the lower sash frame is let down upon the end J, of the lever G, and the hooks are by this means held firmly in the said loops and cannot be released therefrom until the said sash is raised from said lever from the inside. The essence of my invention consists in fastening the blinds closed by the aid of the sash as above described.

Having above described the construction and mode of operating my invention, what I claim as new, and wish to secure by Letters Patent, is—

The shutter or blind-fastening composed of lever G provided with hooks E F attached to the sill H, in combination with notches C D on the blind, to be operated substantially as and for the purpose set forth.

CHARLES H. EDDY.

Witnesses:

T. J. DICKERSON,
A. BABBETT.
